UNITED STATES PATENT OFFICE.

TROY E. AUVEL, OF FAIRMONT, WEST VIRGINIA.

ARTIFICIAL LIMB.

1,076,861.

Specification of Letters Patent.

Patented Oct. 28, 1913.

Application filed July 27, 1912. Serial No. 711,826.

To all whom it may concern:

Be it known that I, TROY E. AUVEL, a citizen of the United States, residing at Fairmont, in the county of Marion and State of West Virginia, have invented certain new and useful Improvements in Artificial Limbs; and I do hereby declare the following to be a full, clear, and exact description of the invention, such as will enable others skilled in the art to which it appertains to make and use the same.

My invention relates to new and useful improvements in artificial limbs.

The prime object of the invention is to provide an artificial limb which, secured to the stump of the limb of the user may be used in walking, etc., simulating the movement of a normal limb.

A further object is to provide means to prevent the bending of the limb much farther while walking than is usual in the case of a normal limb.

A still further object is to provide a cushioning device for the stump of the limb of the user.

Other objects and advantages of my invention will be hereinafter made fully apparent in the specification and pointed out in the claims.

30 In the accompanying drawing I have shown the preferred form which my invention may take.

In said drawing, Figure 1 is a vertical sectional view through my improved form of artificial limb. Fig. 2 is a transverse sectional view therethrough, and Fig. 3 is a vertical sectional view through a portion of a modified form of construction.

In referring to the drawings I have employed numerals of reference, the same numeral designating similar parts throughout the several views.

Referring particularly to Figs. 1 and 2, in which I have shown a form of artificial limb adapted to be used upon the stump of a limb amputated above the knee, 4 is a casing which is formed to simulate a portion of a limb and is provided with a transversely disposed concave partition 5, which is of such a size as, when disposed in the casing 4, it will move downwardly therein to the desired point. The casing 4 is provided with brace bars 6 upon either side which extend slightly below the end of the casing 4 and are pivotally secured near the upper

end of brace bars 7, the lower ends of which are pivotally secured at 15' to the upper ends of a casing 8.

The casing 8 is formed to simulate the lower portion of a limb and will be herein-after more clearly described. The lower end of the casing 8 is in turn provided with a pair of elongated plates 9, which are rigidly secured thereto and extend slightly below the end of said casing. A block 10 formed 65 in the shape of a foot and having its forward or toe portion 11 pivotally secured thereto, is pivoted between the lower ends of said plates 9. The upper end of the block is cut away so that the same may have a 70 slight rocking movement in relation to the casing and said block 10 is normally held substantially at right angles to the casing by means of springs 12, one of said springs being disposed in front of and one behind 75 the pivotal point of said block. The toe piece 11 is also normally held in horizontal position by means of a spring 12a.

As shown in the drawing the casing 8 is hollow and I preferably form the same of 80 relatively stiff and slightly resilient material and provide an air valve 13, by means of which the casing may be inflated. In order that the casing 8 may be normally held extended in alinement with the casing 4, I employ a spring 14 which is connected at one end to the forward and upper portion of the casing and at its upper end to the partition 5 near its central point. The spring is simply of sufficient tension to hold the casing 8 85 in normal relation in respect to the casing 4 but does not prevent movement of said casing relatively when the wearer of the limb is walking.

In order to prevent the casing 8 from 90 being moved to too great a distance, I connect the upper ends of the plates 7 with a cross bar or keeper 15, over which the spring 14 extends. The forward and inner portion of the casing 4 is provided with a standard 95 16, in which a latch 17 is pivotally secured, the latch end thereof being adapted to extend slightly beyond the keeper 15 when the casing 8 is in or nearly in alinement with the casing 4, and which will catch upon said keeper when the limb is bent beyond a predetermined degree. The opposite end of the latch 17 is provided with an operating button 18, which may be formed integrally therewith or pivotally secured thereto, said 105 110

button being disposed in a recess 19 formed in the casing 4 at a point below the partition 5.

In order that the stump of the limb of the user may be prevented from injury, I provide a lining 20 formed of leather, felt or other suitable material, and the upper end of said casing is provided with an interior hollow ring 21. The ring 21 is formed of resilient material such as rubber, etc., and is provided with a valve 22, by means of which the same may be inflated.

The form of artificial limb described by me is adapted to be secured to the stump of the limb of the user by means of a pair of straps 23, which are secured at the front and rear upper end of the casing 4 and extend to the side of the user and preferably to a point adjacent the hip. The ends of said straps are secured to a ring 24, which in turn is secured by a pair of straps 25 to the front and rear portions of a belt 26 adapted to encircle the waist of the user.

When the user of the artificial limb herein described desires to sit down or to have the casing 8 disposed at a greater angle to the casing 4 than is allowed by the latch 17, it is only necessary to depress the operating button 18 to move said latch out of the path 30 of the bolt or keeper 15, whereupon the casing 8 may be bent to the desired point. In order that the joint at the end of the limb may be smooth, I employ webbing 27 connecting the adjacent edges of the casings 4 and 8.

In Fig. 3, I have shown a casing 28, which is adapted to be used upon a limb amputated below the knee and said casing is provided with a pair of plates 9, to which an artificial foot is secured. The casing 28 is provided with a concave partition 29 intermediate its ends and the lower portion of said casing is hollow and provided with a valve 30, by means of which the same may be inflated. The upper end of the casing 28 is provided with a protecting lining 31 similar to the lining 20 of the casing 4, and the upper end thereof is provided with a hollow inflatable ring 32, similar to the ring 21 hereinbefore described. In securing the casing 28 to the limb of the user, I employ straps 33, one upon either side, and secure said straps to a ring 34, which is preferably disposed above the knee of the user. One or

more straps 35 are employed to connect the 55 ring 34 and the ring 24, previously described, which in turn is connected by the straps 25 to the belt 26.

From the foregoing description it will be seen that I have provided an artificial limb 60 formed of relatively stiff inflatable material, which will absorb the shocks incident to walking. It will also be seen that the lower portion of the limb will be thrown forward in a natural manner by the spring 14 when 65 the user is taking a step.

What I claim as new is:

1. An artificial limb comprising a casing, a calf section pivotally secured thereto, a keeper carried by the calf section and extending above the pivotal point of said calf section and casing, a latch within said casing and adapted for engagement with said keeper for limiting the bending movement of the limb while in operation and operating 75 means comprising a latch lever and button whereby said limiting latch may be disengaged from said keeper for allowing the limb to be bent beyond the limit obtained by engagement of the latch. 80

2. An artificial limb comprising a casing having an open upper end adapted to receive the stump of an amputated limb, bars secured to the sides of said casing, a calf section, bars secured to the sides of said calf 85 section extending thereabove and pivoted to said first mentioned bars, a keeper in the lower end of said first mentioned casing at a point above the pivot of said bars, a spring connected to said calf section and 90 casing adapted to normally hold them in alignment, and a limiting latch pivotally secured in the first mentioned casing and adapted for engagement with said keeper. 95

3. An artificial limb comprising a casing, 100 a calf section pivotally secured to the casing, a latch within the casing, a keeper carried by the calf section and engaged by the latch, said casing having a recess in its outer wall, and an operating element in the recess and connected to the latch.

In testimony whereof I have signed my name to this specification in the presence of two subscribing witnesses.
